Fig. 7

Fig. 10

Fig. 8

FIG. 1 is an isometric view of a clamp for securing a reactive member or the like showing our new design and showing the associated wedges in exploded view;

FIG. 2 is a side elevational view, both side views of the clamp for securing a reactive member or the like being essentially identical;

FIG. 3 is a top plan view thereof;

FIG. 4 is a front elevational view thereof;

FIG. 5 is a rear elevational view thereof;

FIG. 6 is a bottom plan view thereof;

FIG. 7 is a side view of the wedges of FIG. 1, the two side views thereof being essentially identical;

FIG. 8 is a top plan view of the wedges;

FIG. 9 is an end view of the small end of the wedges; and

FIG. 10 is an end view of the large end of the wedges.

We claim:

The ornamental design for a clamp for securing a reactive member or the like, as shown and described.
